UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

SHOE FORM

Application filed October 24, 1929. Serial No. 402,121.

This invention relates to an improvement in shoe forms, and more particularly in shoe forms comprising a hollow toe member of resilient material and a crossbar carried by the toe member, which crossbar is pivotally secured at one end to one wall of the toe member and has a sliding engagement at the other end to the other wall whereby the pivotal movement of the bar will cause the expansion or contraction of the walls of the toe member. In my copending application Serial No. 357,947, filed April 25, 1929, now Patent Number 1,740,157, granted Dec. 17, 1929, is shown one type of shoe form embodying this invention, and the present application is an improvement upon the type shown in that application.

The primary object of this invention is to provide a shoe form comprising a hollow toe member of resilient material and a crossbar with means whereby the position of the crossbar may be definitely set, if desired, before the toe member is inserted into the shoe but being so constructed that the position of the crossbar may be shifted after the toe member has been inserted in order to plump out the toe of the shoe to a condition which simulates that of the shoe on the foot of the wearer.

A further object of the invention is to provide means whereby the walls of the toe member may be expanded or contracted without the necessity of unduly increasing the distance between the walls during the expansion or contraction thereof. It is well known that shoe forms of this general construction have previously been made but they are open to the objection that the operation of expanding or contracting the walls of the toe member can not be performed while the toe member is in the shoe, because that operation necessitates an increase in the width of the toe member, which increase would be prevented by the walls of the shoe.

The accompanying drawings disclose several embodiments of the invention, in which: Figs. 1, 2, 3, 4, 5 and 6 are plan views of several shoe forms embodying this invention, with parts broken away:

Fig. 7 is a sectional view taken along the line 7—7 of Fig. 1;

Fig. 8 is a sectional view taken along the line 8—8 of Fig. 2;

Fig. 9 is a sectional view taken along the line 9—9 of Fig. 3;

Fig. 10 is a sectional view taken along the line 10—10 of Fig. 5; and

Fig. 11 is a sectional view taken along the line 11—11 of Fig. 6.

Each of these embodiments comprises a hollow toe member 20 of resilient material having side walls 21 and 22 which terminate in ball flanges designated as 23 and 24 respectively. Each of the forms 20 is provided with a crossbar 25 pivotally secured at the end 26 to the wall 21 of the toe member. As here illustrated the pivoted end of the crossbar is provided with a loop which surrounds a rivet 27 fixed in the flange 23 of the toe member. The flanges 24 in each embodiment are provided with an arcuate longitudinally extending slot 30 with which the free end of the crossbar 25 engages. The flanges 24 are also provided with an arcuate longitudinally extending series of holes 31 preferably located intermediate the slot 30 and the rivet 27, and adapted to receive a tongue which is integral with the crossbar and by which the position of the crossbar is determined. The various embodiments differ in the manner of slidably connecting the crossbar 25 to the flange 24 and in the formation of the tongue which engages the holes 31.

In the embodiment shown in Figs. 1 and 7 the slot 30 receives a rivet 35 about which the free end of the crossbar is bent back upon itself to form a loop 36. The crossbar terminates in a downwardly extending tongue 37 which is so formed that it may enter any one of the holes 31.

In the embodiment shown in Figs. 2 and 8 the slot 30 receives a rivet 40 to which the free end of the crossbar 25 is secured by bending the end of the bar back upon itself to form a loop 41. The free end of the crossbar 25 terminates in an upwardly projecting tongue 42 which may enter any one of the holes 31 in the flange 24. A comparison of the figures illustrating these two embodiments will disclose the fact that in the first

embodiment the free end of the crossbar 25 rests upon the upper face of the flange 24, whereas in the second embodiment the free end rests against the under side of the 5 flange 24.

In the embodiment shown in Figs. 3 and 9 the crossbar 25 is bent back upon itself to form a loop 45 which passes through the slot 30 and terminates in an upwardly projecting tongue 46 which enters any one of the 10 holes 31. Examination of Fig. 9 of the drawing will show that the crossbar 25 extends above the flange 24 and then passes down through the slot 30 below the flange terminating in the upwardly projecting 15 tongue 46.

In the embodiment shown in Fig. 4 the slot 30 is provided with a rivet 50 and the free end of the crossbar is bent back upon 20 itself to provide a loop which surrounds the shank of the rivet, the end portion 51 of the crossbar extending forwardly and terminating in a downwardly extending tongue 52 which may enter any one of the holes 31. 25 It will be noted that in this embodiment the row of holes 31 are spaced forwardly of the slot 30.

In the embodiment shown in Figs. 5 and 30 10 the slot 30 is provided with a rivet 55 which is secured to the free end of the crossbar 25 by an integral loop 56. The crossbar 25 is bent intermediate the distance between its 35 ends to form an integral downwardly projecting tongue 57 which is adapted to enter any one of the holes 31.

In the embodiment shown in Figs. 6 and 40 11 the slot 30 is provided with a rivet 60 to which the free end of the crossbar 25 is secured by a loop 61 formed by bending the end of the crossbar back upon itself. The 45 end of the crossbar forms not only the loop 61 but is again bent forwardly to form a loop 62 which passes around the edge of the flange 24 and terminates in an upwardly projecting tongue 63 which passes into any one of the holes 31.

Due to the construction above described common to each of these embodiments, the crossbar 25 is pivotally secured to the wall 50 12 by means of the rivet 26 passed through the flange 23. The other end of the crossbar is slidably connected to the wall 22 by the engagement of its free end with the slot 30. The crossbars 25 in each of these 55 13 embodiments is provided with an integral projecting tongue which enters one of the holes 31 formed in the flange 24. The pivotal movement of the crossbar upon the rivet 26 causes, by reason of its engagement with the slot 30, the expansion or contraction of the 60 14 walls of the toe member. Such expansion or contraction is a gradual movement and does not necessitate any sudden undue increase in the width of the toe member. The row of 65 15 holes 31 in each of these embodiments is en-

gaged by the projecting tongue of the crossbar so that the walls of the toe member are held at the desired distance apart.

The engagement of the tongue with the 70 holes 31 provides a positive engagement which will not be disturbed by the handling of the shoe provided with this toe member. Moreover, the positive engagement of the tongue and the holes permits that, if desired, the toe member may be set before insertion 75 in the shoe or may be withdrawn from the shoe without disturbance of the adjustment of the walls of the toe member.

While certain embodiments of this invention have been shown and described, I am not limited thereto, since other embodiments could be made without departing from the spirit and scope of the invention as set forth in the following claims.

I claim:

1. A shoe form comprising a hollow toe member of resilient material, the walls thereof being flanged, a crossbar pivotally attached at one end to the flange of one wall, the flange of the other wall having an arcuate longitudinally extending slot and an arcuate longitudinally extending series of holes, the slot forming a guide for the free end of the bar whereby upon the pivotal movement of the crossbar the free end thereof moves relative to the slot and the walls of the toe member are expanded or contracted, and a tongue carried by the crossbar for engaging one of the holes and thereby holding the crossbar against such pivotal movement.

2. A shoe form comprising a hollow toe member of resilient material, the walls thereof being flanged, a crossbar pivotally attached at one end to the flange of one wall, the flange of the other wall having an arcuate longitudinally extending slot and an arcuate longitudinally extending series of holes, the slot forming a guide for the free end of the bar whereby upon the pivotal movement of the crossbar the free end thereof moves relative to the slot and the walls of the toe member are expanded or contracted, and a tongue integral with the crossbar for engaging one of the holes and thereby holding the crossbar against such pivotal movement.

3. A shoe form comprising a hollow toe member of resilient material, the walls thereof being flanged, a crossbar pivotally attached at one end to the flange of one wall, the flange of the other wall having an arcuate longitudinally extending slot and an arcuate longitudinally extending series of holes, the slot forming a guide for the free end of the bar whereby upon the pivotal movement of the crossbar the free end thereof moves relative to the slot and the walls of the toe member are expanded or contracted, and a tongue formed by the tip 120 115 125 130

of the crossbar for engaging one of the holes and thereby holding the crossbar against said pivotal movement.

4. A shoe form comprising a hollow toe member of resilient material, the walls thereof being flanged, a crossbar pivotally attached at one end to the flange of one wall, the flange of the other wall having an arcuate longitudinally extending slot and an arcuate longitudinally extending series of holes, a rivet movable in said slot to which rivet the free end of the crossbar is attached, whereby upon the pivotal movement of the crossbar the rivet is moved in the slot by the free end of the bar and the walls of the toe member are expanded or contracted, and a tongue carried by the crossbar for engaging one of the holes and thereby holding the crossbar against such pivotal movement.

5. A shoe form comprising a hollow toe member of resilient material, the walls thereof being flanged, a crossbar pivotally attached at one end to the flange of one wall, the flange of the other wall having an arcuate longitudinally extending slot and an arcuate longitudinally extending series of holes located intermediate the slot and the pivoted end of the crossbar, a rivet movable in said slot to which rivet the free end of the crossbar is attached, whereby upon the pivotal movement of the crossbar the rivet is moved in the slot by the free end of the bar and the walls of the toe member are expanded or contracted, and a tongue carried by the crossbar for engaging one of the holes and thereby holding the crossbar against such pivotal movement.

Signed by me at Boston, Massachusetts,
this 23rd day of October, 1929.
